[57] **CLAIM**

The ornamental design for a water distiller unit, substantially as shown and described.

DESCRIPTION

FIG. 1 is a perspective view taken from the top, front and left side of a water distiller unit showing my new design;

FIG. 2 is a front elevational view thereof;

FIG. 3 is a right side elevational view thereof;

FIG. 4 is a rear elevational view thereof; and

FIG. 5 is a bottom plan view thereof.

The center of the electric cord has been broken away in FIGS. 3, 4 and 5 to indicate indeterminate length.
